CLAIM

We claim the ornamental design for buttons for a load control device, as shown and described.

DESCRIPTION

FIG. 1 is a perspective view of buttons for a load control device according to a first embodiment of our new design; and,

FIG. 2 is a front view thereof.

The portions of the drawings appearing in broken line are for environment only and do not form a part of the claimed design. The left side, right side, top, bottom, and rear views form no part of the design and are omitted.
